CLAIM

I claim the ornamental design for an oven grate, as shown and described.

DESCRIPTION

FIG. 1 is a perspective view of an oven grate showing my new design;

FIG. 2 is a top plan view thereof;

FIG. 3 is a bottom plan view thereof;

FIG. 4 is a side elevational view thereof, the opposite side being identical;

FIG. 5 is an end elevational view thereof; and,

FIG. 6 is an end elevational view of the opposite side of FIG. 5.
